Patented Dec. 17, 1918.

UNITED STATES PATENT OFFICE.

FREDERICK J. HORNBERGER, OF BRIDGEPORT, CONNECTICUT.

STOP MECHANISM FOR PHONOGRAHS.

1,287,693.

Specification of Letters Patent. Patented Dec. 17, 1918.

Application filed November 26, 1917. Serial No. 203,909.

To all whom it may concern:

Be it known that I, FREDERICK J. HORNBERGER, citizen of the United States, residing at Bridgeport, in the county of Fairfield and State of Connecticut, have invented certain new and useful Improvements in Stop Mechanism for Phonographs; and I do hereby declare the following to be a full, clear, and exact description of the invention, such as will enable others skilled in the art to which it appertains to make and use the same.

My invention relates to an automatic attachment for phonographs or talking machines of like character having a turn table and a recording arm, and it consists in the arrangement and combination of mechanism for automatically stopping the machine at the end of the record without regard to the size of the disk or record, thus obviating the necessity of setting the mechanism for records of varying sizes. It also enables the operator to interrupt the record at any stage and engage the needle at any desired point in the record without stopping the machine or interfering with the operation of the stop mechanism.

Referring to the drawings:

Figure 1 represents a plan view of the stop mechanism in idle position, broken view of the motor board and sectional view of the arm stud on line *a a* of Fig. 10;

Fig. 2 is a similar view of the stop mechanism showing said stop mechanism in operation;

Fig. 3 is an enlarged detail view of the pinion throw-out lever;

Fig. 4 is an enlarged broken view of the locking lever, end elevation of the segment lever, elevation of the trip lever and trip rod showing the positions they occupy when the stop motion mechanism is in operation;

Fig. 5 is an enlarged view of the trip lever and trip rod showing their positions when the stop motion mechanism is at rest;

Fig. 6 is an enlarged broken view of the segment lever and front end elevation of the trip lever;

Fig. 7 is an enlarged broken view of the motor board, star wheel and its supporting frame;

Fig. 8 is an enlarged broken view of the motor board, and side elevation of the intermediate gear;

Fig. 9 is a detail broken view of the driver carried by the recording or tone arm;

Fig. 10 is a reduced broken view of the tone arm of a phonograph; and

Fig. 11 is an enlarged detail view of a part of the stop mechanism.

The stop mechanism is located on the motor board 1, which underlies the turn table—not shown. The motor board has the usual recess 2 and the disk shaft 3 projecting therefrom. Projecting laterally from this shaft is the usual turn table driving pin 4, which pin is extended beyond the recess to actuate the stop mechanism and is provided with the head 5 adapted to engage the teeth of the star wheel 6 and effect a step by step rotation of said wheel. This wheel is secured to the shaft 7, Fig. 7, journaled in the frame 8, which frame is journaled on the screw 9 secured to the motor board.

locking lever 36. This locking lever is pivotally supported on screw 37, and its forward end 38 is normally held against the starting lever 39 by the spring 40.

5 41, Fig. 10, is a stud projecting from the underside of the tone arm 42, and to this stud is secured the driver 43 adapted to actuate the lever 22 in the manner presently to be more fully described. 44 is the usual sound 10 box carrying its pin 45. 46 is a lever pivotally supported on the screw 47 secured to the lower extension 48 of the frame 8. Lever 46 is provided with the forked opening 49, Fig. 3, adapted to receive the lower projecting end of the screw 50 carried by the segment lever.

When the machine is ready to operate, the segment lever will be approximately in the position shown in Fig. 1. When in this position, the screw 50 will rest against the bottom 51 of the forked opening of lever 46, Fig. 3, and when the lever is moved forward by the tone arm it will cause the frame 8 to turn on its pivoted support and carry the 25 pinion 10 out of contact with the large gear 11. -

Actuating the starting lever 39 to operate the machine will also cause its notch 52 to engage the locking lever 36 and thus 30 temporarily connect the machine operating mechanism with the stop mechanism to start the machine. The needle is brought in contact with the record as usual and the star wheel will continue running idle until released by the inward travel of the tone arm whose underlying lever 43 will engage the trip lever arm 27, through the medium of the flexible spring 43^a, and turn the segment lever on its pivotal support in the direction 35 of arrow b, Fig. 1, until the contact between the screw 50 and the bottom of the forked opening of the lever 46 is sufficiently broken to permit the spring 52^a to actuate the frame 8, and bring the pinion 10 into mesh with 40 the large gear 11.

The contact of the spring 43^a with the arm 27 will also tilt the trip lever 24 and cause its roller, 30, Fig. 4, to elevate the trip rod 33 whose underlying teeth 53 is adapted at 45 the proper time, to engage the blade 54 located at the bottom of the narrow slot 55 of the swivel block 32.

When the end of the disk record has been reached, the inward movement of the needle 55 arm will cease, but the geared mechanism will continue in operation long enough to release the trip lever 24 from its contact with the spring 43^a on the driver 43 and permit the trip lever to drop. This will also allow 60 the trip rod 33 to drop with the underlying teeth 53 in contact with the blade 54, and thus effect a direct pull on the locking lever 36 and release the same from the notch 52 of the starting lever 39, so that the spring 56 65 can rotate said lever and bring the entire

mechanism of the machine into a state of rest. When the tone arm is being manually returned, the driver 43 will engage the roller 57, underlying the extension 58 of the lever 22, and cause a reverse movement of the segment lever until the driver 43 can clear itself from the roller 57. This will leave the segment lever in the proper position to be picked up again by the spring of driver 43. The tone arm is now free and at liberty to 75 engage a record of any dimension.

The sole purpose of the actuating mechanism, located between the segment lever and the driver 5, is to continue the travel of the segment lever and carry the arm 27 away 80 from the halted tone arm far enough for the trip lever and its roller 30 to drop, and permit the teeth of the trip rod to engage the blade 54 and release the locking lever 36. The object of the frictional pinion 17 is to 85 compensate for any difference between the travel of the needle or tone arm and the large gear 11. In other words, it is not necessary that the inward movement of the tone arm be accurately timed with the rotation of the 90 gear 11, as the pinion will readily slip to compensate for any difference that may occur.

As the track of records are more or less wavy, the tone arm must necessarily follow 95 any irregularity of this kind. To enable the tone arm to move in accordance with the wavy track of the record, I employ the light sensitive spring 43^a, which contacts with the arm 27 of the trip lever mechanism. This 100 spring will enable the tone arm to have whatever vibration is necessary to conform to the irregular track of the record and also exert sufficient pressure to actuate the segment lever.

As before mentioned, the mechanism above described is adapted to automatically stop the machine at the end of a record regardless of its size. The point of stoppage for the tone arm is always at the end of a record, 110 whether the record be short or long, and the tripping of the locking lever cannot take place until after the tone arm has halted; therefore, the size of the record has no effect or bearing on the action of the tripping 115 mechanism, which only operates at the end of the record.

Having thus described my invention, what I claim is:—

1. A stop attachment for disk phonographs having a rotatable disk shaft, starting lever and pivoted tone arm, of a segment lever, means carried by the tone arm for actuating said lever, an intermediate gear, a frictionally supported pinion carried by the 120 gear and meshing with the segment lever, means for imparting an intermittent movement to the gear from the disk shaft, means carried by the segment lever for interrupting such movement, a locking lever, a trip 125

rod connected therewith, a trip lever for the rod, and means carried by the segment lever for actuating the trip rod and releasing the locking lever from its engagement with the 5 starting lever.

2. In combination with the disk shaft, tone arm and starting lever of a phonograph, of stop mechanism comprising a star wheel actuated from the disk shaft, a pivoted support for the star wheel, an intermediate gear, a pinion carried by the support for actuating the gear, a segment lever associated with the gear by a frictionally supported pinion, flexible means on the tone 10 arm for actuating the segment lever, and means on the segment lever for releasing the locking lever from contact with the starting lever.

3. The combination with the tone arm, 20 disk shaft and starting lever, of a locking lever temporarily engaging the starting lever, a pivotally supported trip rod carried by the locking lever, a segment lever, a driver rotatably connected to the disk shaft, 25 mechanism located between the driver and segment lever for imparting an intermittent movement to the segment lever after the tone arm is halted, a trip lever on the segment lever, means on the tone arm to engage the 30 trip lever and actuate the segment lever toward the disk shaft, means carried by the trip lever to render the trip rod inactive while a record is being played, and means 35 on the segment lever adapted to be engaged by the trip rod to release the locking lever after the tone arm is halted.

4. In combination, a segment lever, a star wheel, a pivoted support therefor, an intermediate gear, a pinion carried by the star

wheel meshing with the gear, a toothed segment lever, a frictionally supported pinion carried by the gear and in mesh with said lever, and means carried by the lever to disengage the star wheel pinion from the gear.

5. In combination with the disk shaft, 45 strating lever and tone arm of a phonograph, of stop mechanism comprising a pivoted lever, a locking lever engaging the starting lever, means connecting the locking lever with said pivoted lever, a lever carried 50 by the tone arm, a spring carried by said lever for actuating said pivoted lever, said pivoted lever normally idle until actuating by the tone arm, means intermediate of the pivoted lever and disk shaft and actuated 55 by the disk shaft to move in unison with the pivoted lever when said lever is under the control of the tone arm and move said pivoted lever out of contact with the tone arm at the completion of a record, means for releasing the locking lever from the starting lever, the tone arm lever adapted to engage the pivoted lever and return said pivoted lever to its normal idle position.

6. In combination with the tone arm and 60 stop mechanism of a phonograph, of a pivoted lever operatively connected with said mechanism and actuated by the tone arm and remain under the control of said arm during its inward travel, flexible means 65 carried by the tone arm to serve both as a driver for the lever and as means to permit a slight vibration of said arm and thus enable it to follow any irregularity in the track of a record.

75 In testimony whereof I affix my signature,

FREDERICK J. HORNBERGER.
